UNITED STATES PATENT OFFICE.

GEORGE R. TOWNSEND, OF WINCHESTER, MASSACHUSETTS, ASSIGNOR, BY MESNE ASSIGNMENTS, TO GILLESPIE EDEN CORPORATION, A CORPORATION OF DELAWARE.

CLOTHES-WRINGER.

1,401,210.

Specification of Letters Patent. Patented Dec. 27, 1921.

Application filed May 7, 1920. Serial No. 379,511.

To all whom it may concern:

Be it known that I, GEORGE R. TOWNSEND, a citizen of the United States, and a resident of the city of Winchester, in the county 5 of Middlesex and State of Massachusetts, have invented certain new and useful Improvements in a Clothes-Wringer; and I do hereby declare that the following is a full, clear, and exact description of the same, reference being had to the accompanying drawings, and to the numerals of reference marked thereon, which form a part of this specification.

This invention relates more particularly to 15 an improved type of a clothes wringer wherein the reversible water board is replaced by an improved drain trough disposed below the wringer rolls and provided with inclined water boards and a pipe drain.

20 It is an object of this invention to provide a clothes wringer with an improved drain mechanism.

It is also an object of the invention to provide a clothes wringer with a stationary 25 drain trough having a drain pipe at one end thereof.

Another object of the invention is the construction of a clothes wringer having a drain trough provided with a drain pipe and inclined drain boards.

30 It is an important object of this invention to provide an improved type of a clothes wringer of simple and improved construction, and wherein a drain trough and pipe 35 are positioned below the wringer rolls which are adjustable by means of a single adjusting screw and spring.

Other and further important objects of 40 this invention will be apparent from the disclosures in the drawings and specification.

The invention (in a preferred form) is 45 illustrated in the drawings and hereinafter more fully described.

On the drawings:—

45 Figure 1 is a side elevation of a wringer embodying the principles of this invention.

Fig. 2 is an end view thereof.

Fig. 3 is an enlarged section taken on line 3—3, of Fig. 1, with parts in elevation.

50 Fig. 4 is a detail section taken on line 4—4 of Fig. 1.

Fig. 5 is an enlarged fragmentary detail section taken on line 5—5 of Fig. 2.

Fig. 6 is a sectional view taken on line 55 6—6 of Fig. 5.

As shown on the drawings:—

The reference numeral 1 indicates a wringer frame, having rigidly secured on one end thereof a gear box 2, within which the driving gears and the reversible roller 60 clutch mechanism is mounted. Secured to the gear box 2, is a vertical shaft casing 3, for inclosing a wringer driving shaft. A removable hood or yoke 4 is provided to close the upper portion of the frame 1. Latches 65 5 and tie rods 17, are provided for holding the yoke 4 in position.

Mounted in the lower corners of the frame 1, are blocks 6 and 7, between which is clamped a drain trough 8, by means of tie 70 bolts 9, which project longitudinally through said trough and connect said blocks 6 and 7, as shown in Fig. 6. The block 7, is provided with an outlet passage 10, and has secured on the outer end thereof a drain pipe 75 or spout 11. Integrally formed, or rigidly secured on the longitudinal edges of the drain trough 8 are downwardly inclined drain boards 12 provided with upright end flanges 13. The drain trough 8, closes the 80 bottom of the wringer frame, and is positioned below the wringer rolls 14. The rolls 14, are provided with axial shafts, or spindles 15 which project into vertical guide slots 16, provided in partition plates 18. 85

Mounted in each end of the frame 1, are a pair of oppositely disposed bearing guides 19, between which lower and upper spindle bearing blocks 20 and 21 respectively are placed. Roll guards 22, are provided to 90 protect the ends of the rolls 14. Disposed longitudinally in the wringer frame above the upper roll 14, is a convex or upwardly curved wringer spring 23, provided at its middle portion with a socket or detent 24, 95 for receiving the lower end of an adjusting screw 25. The screw 25, projects upwardly through a longitudinal slot 26, provided in the top wall of the frame yoke 4. A hand wheel 27, is secured on the upper projecting 100 end of the screw 25. The ends of the spring 23, seat in notches provided in the upper bearing blocks 21, as shown in Fig. 5. Plates 28, are secured on the top of the upper bearing blocks 21, for the purpose of retaining 105 the ends of the spring 23 in place.

Rigidly secured to the middle portion of the inner surfaces of the sides of the frame yoke 4, are a pair of oppositely disposed release brackets 29, having link pins 30, se- 110

cured thereto. The pins 30, project into slots 31, provided in links 32, mounted adjacent the release brackets 29. Holes are provided near the lower ends of the links 32, 5 for receiving the trunnions 33, of a knuckle 34. The knuckle 34, separates the links 32, and is provided with a threaded passage through which the screw 25, is threaded. The upper ends of the links 32, contact the 10 inner surface of the top wall of the frame yoke 4.

For the purpose of starting the wringer and for reversing the rotation of the wringer rolls 14, a control lever or handle 35, is provided and projects into the gear box 2, to 15 permit shifting of a clutch mechanism to connect up the rolls with the driving shaft in the shaft casing 3. The driving shaft may be connected to receive a drive from a 20 motor or any other source of power.

The operation is as follows:—

The wringer rolls 14, have the spindles 15, thereof journaled in the bearing blocks 20 and 21. The plate spring 23, which engages 25 in the upper bearing blocks 21, is adapted to be stressed or depressed by turning the adjusting screw 25, by means of the hand wheel 27. The screw threads downwardly through the knuckle 34, and 30 the inner end of said screw being engaged in the spring detent 24, acts to force the spring downwardly. The upper bearing blocks 21, are thereby moved downwardly between the guide members 19, thus moving 35 the upper roll 14, toward the lower roll, an amount depending upon the adjustment of the screw 25.

The wringer is started by turning the 40 lever 35, in one direction from its normal position. A drive from the shaft within the shaft casing 3, is thus transmitted by means of the gear mechanisms in the gear box 2, to the wringer rolls 14. The direction of rotation of the rolls 14, may be reversed by 45 throwing the starting lever 35, in an opposite direction.

When the wringer is operating, wet 50 clothes may be run between the wringer rolls 14, for wringing the greater part of the water from the wet clothes. The water removed from the clothes falls into the drain trough 8, and upon the inclined drain boards 12. The water from the trough 8, flows out 55 through the passage 10, and through the drain spout 11. The water falling on the boards 12, is permitted to run back into the receptacle holding the wet clothes. While

one of the boards 12, acts as a drain the other serves as a support for receiving the clothes as they leave the wringer rolls. 60

If at any time it becomes necessary to release or separate the rolls 14, in a hurry, the quick release mechanism provided in the frame yoke 4, may be brought into play. This is done by merely swinging the adjusting screw 25 to one side or the other longitudinally of the wringer frame in the yoke slot 26. 65

By swinging or tipping the screw 25, the inner end thereof is swung out of the spring 70 detent 24, thereby instantly releasing the wringer spring 23, and thereby permitting the wringer rolls 14, to separate to permit heavy clothing or an article mixed in clothes to pass between the rolls 75 without resulting in damage. The trunnions 33, of the knuckle 34, permit the knuckle to be rotated by the screw 25. The slots 31, in the links 32, permit adjustment of said links with respect to the release 80 bracket pins 30.

I am aware that numerous details of construction may be varied through a wide range without departing from the principles of this invention, and I therefore do not 85 purpose limiting the patent granted otherwise than necessitated by the prior art.

I claim as my invention:—

1. The combination with a clothes wringer, of blocks therein, one of said blocks 90 having a drain passage therethrough, a drain trough in said wringer between said blocks, tie bolts connecting said blocks for holding said drain trough clamped in position, and a drain spout secured on said passed block to permit the escape of a liquid 95 from said trough.

2. A clothes wringer having a drain comprising a pair of blocks, a trough therebetween, means connecting said blocks to hold the trough clamped between said blocks with said blocks closing the ends of said trough, outwardly projecting drain boards integrally formed on opposite sides of said trough, and flanges integrally formed on 105 the opposite ends of said drain boards.

In testimony whereof I have hereunto subscribed my name in the presence of two subscribing witnesses.

GEORGE R. TOWNSEND.
